UNITED STATES PATENT OFFICE.

ADDISON CROSBY, OF NEW YORK, N. Y.

IMPROVEMENT IN FLUE-CLEANERS.

Specification forming part of Letters Patent No. 156,543, dated November 3, 1874; application filed September 22, 1874.

To all whom it may concern:

Be it known that I, ADDISON CROSBY, of New York city, N. Y., have invented certain new and useful Improvements in Flue-Cleaners; and I do hereby declare that the following is a full and exact description thereof, reference being had to the accompanying drawings making a part of this specification.

This invention relates to that class of flue-cleaners (for cleaning the fire-flues of boilers) in which a jet of steam is thrown into a movable pipe to be applied to each flue, so as to create a vacuum-draft, which draws out the soot from the open flue, and may be considered as an improvement on the flue-cleaner described in N. W. Wheeler's patent of 1865.

In the drawings similar letters refer to like parts.

Figure 1 is a side elevation; Fig. 2, a vertical section, showing the instrument applied to a flue, but not in action. Figs. 3, 4, 5, 6, and 7 are details.

B represents a section of a boiler, and F a section of a flue. C is a double reducing-nozzle of cast metal. The mouth *m*, which is applied to and over the flue to be cleaned, is faced with a rubber ring, *a*, and is of the full diameter of the flue—say, four inches. The discharge-mouth *d* is about two inches diameter, being a reduction as one to four from the diameter of the flue-mouth *m*. This reduction greatly increases the power of the draft. I is a reducing injector-pipe, being about three-quarters of an inch in diameter at its butt, where it is screwed into the steam-mouth *s* of the reducing-nozzle, and being about half an inch at its nozzle, which discharges its jet of steam about two inches within the discharge-mouth *d*. I prefer that this should be a reducing-pipe, but the reduction is not indispensable. E is a pipe some two or three feet long and about three-quarters of an inch diameter, and is screwed to the nozzle at its mouth *s*. This pipe is surrounded by a wooden jacket, *e*, so that it may be used as a handle in applying the instrument. W is an angle valve-seat screwed to the other end of pipe E, and is provided with a spring-valve, V, which controls

the admission of steam to pipe E. N is a screw-nozzle secured to seat W, for the attachment of the three-quarter-inch flexible steam-hose S. H is a stirrup-handle attached to seat W for convenience in applying the instrument. G is a gripe-lever, pivoted at one end to stirrup H and in the middle to the valve-rod *r*, so that the hand of the operator, while grasping handle H, may also grip lever G, and thus admit the steam.

The operation is as follows: Pipe S is attached to a steam-nozzle of the boiler. The mouth *m* is then applied over the flue to be cleaned, and pressed against it so as to make a joint. By gripping lever G the valve V is opened, and a jet of steam is admitted which rushes through pipe E and injector I, into and out of discharge-mouth *d*, thereby creating a vacuum, (the power of which is intensified by "reduction,") which powerfully draws a current of air through the open flue, thus clearing out its soot and other injurious contents.

The chief feature of my invention consists in having the discharge-mouth *d* of a much-reduced area, as compared with the flue-mouth.

Instead of taking in the steam, as shown, at an angle to the line of discharge, it is possible to take it in a direct line from the boiler at point marked *x*, and the same result will ensue.

I claim—

1. The combination of the stirrup-valve G, steam-jet I, bent nozzle C, constructed and operating substantially as set forth.
2. The combination of stirrup H, lever G, valve V, valve-seat W, rod *r*, and spring *o*, substantially as set forth.
3. The valve-seat W, in combination with stirrup H and pipe E, substantially as set forth.

Witness my hand this 29th day of July, 1874.

ADDISON CROSBY.
